UNITED STATES PATENT OFFICE

2,667,672

BOOK STERILIZING MACHINE

Marshall Eltinge, Salt Lake City, Utah

Application October 9, 1950, Serial No. 189,197

3 Claims. (Cl. 21—76)

1

This invention relates to sterilizing devices and has particular reference to apparatus for the sterilization of books, papers and the like.

One of the primary objects of my invention is to provide apparatus for sterilizing books and the like which will efficiently render them free from germs and contamination without injury to the pages or bindings.

Another object of my invention is to provide apparatus of the character described above in which books of various sizes may readily be accommodated.

Another object of my invention is to provide a book-sterilizing machine having novel means for mixing a disinfectant or germicide with air.

Another object of my invention is to provide such a machine having novel means for humidifying and heating a gaseous disinfectant.

Another object of my invention is to provide a book-sterilizing machine incorporating a novel riffling device for automatically separating the leaves or pages of books as they travel through the machine.

A further object of my invention is to provide novel means for directing currents of gaseous disinfectant into and through the interior of articles undergoing sterilization.

Other objects and advantages of this invention it is believed will be apparent from the following detailed description of a preferred embodiment thereof as illustrated in the accompanying drawing.

In the drawings:

Figure 1 is a perspective view illustrating a preferred embodiment of my invention.

Figure 2 is a sectional elevation taken substantially on the line 2—2 of Figure 1.

Figure 3 is a sectional elevation taken substantially on the line 3—3 of Figure 2.

Figure 4 is a detail view of the book trough and clamp.

Figure 5 is a sectional elevation taken substantially on the line 5—5 of Figure 4.

Referring now to the drawings, the sterilization unit embodying my invention includes a generally rectangular sterilizing chamber 10 defined by a top 11, double side walls 12 and 13, double end walls 14 and 15, and bottom wall 16. Longitudinal chain conveyors 17 are mounted within the chamber 10 on suitable framework 18. A plurality of conveyors 17 are disposed within the chamber, one above the other, although only a single conveyor is shown in the drawings for clarity of illustration.

Each of the conveyors 17 includes a pair of 55 a horizontal axis. Inner walls 41 form an air

2

parallel side chains 19 driven by sprockets 20 connected with a motor 21 by means of suitable transmission 22. Means are provided for supporting the books 23 in their travel through the chamber 10, and as shown in the drawings these means may include the transverse channel or trough members 24 which are connected at each end to one of the side chains 19. The members 24 may be pivotally connected to shafts 25 for adjustment. The covers of the books are seated in the V-shaped troughs 24, the trough members being spaced sufficiently far apart so that the book covers assume an inverted V-shape, with the pages or leaves depending freely therebetween. Longitudinal hold-down members 26, triangular in cross-section, may be provided to securely maintain the books in place. Manually adjustable clamps 27 may also be provided for adjustment of the hold-down members 26. These clamps 27 may include U-shaped frame members 28 pivotally connected to stub shafts 29 and secured thereto by means of nuts 30. The hold-down members 26 are adjustably mounted on the frames 28 by means of threaded elements 31 and locking members 32 which are provided with levers 33 to facilitate the operation of the locking members.

As the books progress through the chamber 10 they are subjected to sterilizing rays from the ultra-violet lamps 34 which are located at suitable intervals intermediate the conveyors 17 so that irradiations from the lamps may be directed both upwardly against the underside of the upper row of books and downwardly against the top of the lower row of books.

Means are provided for separating and riffling the pages of the books as they travel through the chamber, and as shown in the drawings, these means may include the resilient brushes 35 which are mounted on rotating transverse rods 36. As shown best in Figure 3, these brushes are slightly curved and offset with respect to the direction of travel of the books so that the fingers 37 may sequentially engage the depending leaves of the books and thus separate them to permit the penetration of sterilizing rays from the lamps 34 and also permit the penetration of sterilizing gases which are introduced into the chamber in the manner described below.

A blower housing 38 is mounted beneath the chamber 10, the unit 38 having exterior walls 39 forming a continuation of the walls 12, 13, 14 and 15. A plurality of fans or blowers 40 are mounted within the housing 38 for rotation about

passageway from the chamber 42 formed by the double side walls 12 to the chamber 43 formed by the double side walls 13. The fans 40 are driven counterclockwise as seen in Figure 2 by the motor 44, drawing air through the inlet 45.

Means are provided to inject a predetermined amount of liquid disinfectant into the air which is discharged from the blowers 40, and as shown in the drawings, these means may include the perforated tubular supply line 46, upon which the blowers 40 are journaled. The hollow axles 47 of the fans 40 are likewise perforated to permit formaldehyde or other disinfecting gas to be pumped from the germicide generator 48 through the perforations in the supply line 46 and into the air stream produced by the fans. The speed of rotation of the fans 40 is regulated together with the formaldehyde input in order to obtain the proper ratio of 17.5 g. of gas per cubic meter of space used.

Means are provided for heating and humidifying the sterilizing gas thus produced, and as shown in the drawings, particularly Fig. 2, these means may include the horizontal plates 49 extending through substantially the entire length of the chambers 42 and 43. These plates are heated by means of heating elements 50. Perforated overhead water pipes 51 are mounted longitudinally in the chambers 42 and 43 and are arranged to drip water onto the plates 49 to form steam upon contact with the heated plates. Copper wire screening 52 is suspended in inverted U-shape by means of longitudinal rods 53, the screens being connected with the plates 49 at suitable intervals to be heated by conduction therefrom. As the germicide emerges from the outlet 54 of the blowers, it rises to mix with the steam laden air in the chamber 43. After being humidified and heated by the steam adjacent the hot plate 49, the vapor rises. Any loss in heat is restored at least partially when the germicide passes through the heated copper screening 52.

The humidified and heated gaseous disinfectant is then forced into the chamber 10 through triangular apertures 55, those on the inner wall 13 being identical in size and shape and in horizontal and vertical alignment with the apertures on the inner wall 12. It will be noted that the books 23 assume a triangular shape when they are supported on the conveyors 17. The apertures 55 are made to roughly correspond in size and shape with the triangle formed by the books 23. The motors 21 are provided with stopping and starting means (not shown) which permits intermittent travel of the conveyors 17 through the chamber 10. The travel of the conveyors between pauses is arranged so that any one row of books will stop in a direct line between opposite apertures 55. The covers of the books form a semi-enclosure through which the germicide travels in substantially a direct current from the chamber 43 to the chamber 42, resulting in a direct and thorough penetration of the germicide into the interior of the books. Turbulent flow of the gas is obtained by passing it through the copper screening 52 before entrance into the sterilizing chamber 10, thus tending to cause the pages of the books to be rifled or separated.

While I have shown and described a specific embodiment of my invention, I do not limit myself to the exact details of the construction set forth, and the invention embraces such changes, modifications and equivalents of the parts and their formation and arrangement as come within the purview of the appended claims.

I claim:

1. In a device for sterilizing books and the like, walls forming a chamber, conveyors for moving books and the like longitudinally through said chamber, V-shaped channel members secured to said conveyors transversely thereof, said channel members having upstanding arms forming troughs and spaced so that the edges of the covers of said books may be inserted into said troughs for supporting the books with the pages thereof depending freely between the covers, hold-down members operably associated with said channel members for clamping the book covers in place, means for introducing a gaseous germicide into said chamber, and means for riffling the pages of the books as they progress through the chamber.
2. In a device for sterilizing books and the like, walls forming a chamber, conveyors for moving books and the like longitudinally through said chamber, channel members secured to said conveyors transversely thereof, said channel members having upstanding arms forming V-shaped troughs and spaced so that the edges of the covers of the books may be inserted in said troughs for supporting the books with the pages thereof depending freely between the covers, hold-down members operably connected to said channel members for clamping the book covers in place, said hold-down members being V-shaped and nested in said troughs, means for introducing a gaseous germicide into said chamber, and means for riffling the pages of the books as they progress through the chamber.
3. In a device for sterilizing books and the like, walls forming a chamber, conveyors for moving books and the like longitudinally through said chamber, channel members secured to said conveyors transversely thereof, said channel members having upstanding arms forming V-shaped troughs and spaced so that the edges of the covers of the books may be inserted in said troughs for supporting the books with the pages thereof depending freely between the covers, hold-down members for clamping the book covers in place, said hold-down members being V-shaped and nested in said troughs, means for pivotally and swingably connecting said hold-down members to said channel members, means for introducing a gaseous germicide into said chamber, and means for riffling the pages of the books as they progress through the chamber.

MARSHALL ELTINGE.
